UNITED STATES PATENT OFFICE.

HENRY MESSEY, OF ROXBURY, MASSACHUSETTS.

IMPROVEMENT IN CALORIC-ENGINES.

Specification forming part of Letters Patent No. 40,178, dated October 6, 1863.

To all whom it may concern:

Be it known that I, HENRY MESSEY, of the city of Roxbury, county of Norfolk, and State of Massachusetts, have invented an Improvement in Hot-Air Engines; and I do hereby declare that the following, taken in connection with the drawing which accompanies and forms part of this specification, is a description of my invention sufficient to enable those skilled in the art to practice it.

This invention pertains to that type of hot-air engines which pass the gaseous products of combustion as well as heated air from the furnace into the engine-cylinder to actuate the piston therein; and the invention consists, first, in the introduction of steam into the furnace, so that it will be decomposed by the heat thereof into its constituent gases, and will in this gaseous form increase the impelling medium by mingling with its components and passing with them into and then out of the cylinder; and, second, in controlling the speed of the engine by causing its regulator or governor to actuate a valve to adjust the supply of steam to the requirements of the work to be performed by the engine, admitting steam freely when the amount of work is large, and the engine tends to run below speed, and shutting the steam off more or less, as required, when the work is light and the engine tends to run above speed, and in this latter case storing steam up in the boiler to a pressure limited by the gage of the safety-valve, to be used as a reserve force when more work is put upon the engine. In the first part of my invention the result upon the engine of the introduction of steam in said manner differs widely from the introduction of water into the furnace. In the finely-divided or minute atomic condition of steam when subjected to a sufficient degree of heat, it is at once decomposed into its constituent gases, which do not again in the engine combine to form steam or water. Water introduced into the furnace has first to be converted into steam therein before it can be decomposed, and in this form of steam much of it passes into the engine, where it condenses, and, mingling with some of the products of combustion, a highly-corrosive fluid is formed, which is extremely destructive to the material of the engine.

When steam is introduced according to my invention, the engine should be started and worked long enough to establish a good degree of combustion in the furnace, so that the heat thereof will decompose the steam when admitted; and before the working of the engine is stopped the steam should be shut off, so that as the fire wanes no steam shall pass into the engine in an undecomposed state, or in the form of condensable vapor. This and other necessary regulation of the amount of steam to be supplied to the furnace, and the times at which it is to be supplied, may be effected by the use of suitable valves, which may be operated by hand or automatically by the regulator of the engine, or in part by both. The steam which is admitted into the furnace may be generated in any of the well-known ways.

The accompanying drawing shows in plan so much of a hot-air engine and steam-boiler as is needed for a full understanding of my invention.

a represents the cylinder of a caloric-engine; *b*, a pipe through which the "exhaust" from the engine can pass into the boiler *c*; or steam may be generated by a fire kindled under the boiler, which is represented as one of the plain vertical fire-tube type.

d is the pipe by which steam generated in the boiler is conducted to the furnace, either above or below the grates and fuel, or both above and below the fuel the steam must be introduced in immediate juxtaposition thereto in order to insure its desired decomposition, and to prevent the passage of any of it into the engine in the form of condensable vapor. If it be preferable to have the requisite quantity of steam enter the furnace in fine jets or streams, then the apertures connecting the steam-pipe and furnace must be modified accordingly.

The furnace is shown in dotted lines in the drawing, and a throttle-valve is shown as located in pipe *d*, to which valve any suitable well-known form of regulator may be connected, to regulate automatically the speed of the engine by controlling the amount of steam which passes into the furnace. Another suitable valve may be located in pipe *d* to shut off the steam from the furnace before stopping the engine, and to keep it shut off therefrom.

until a suitable time after the engine is started.

It is obvious, of course, that before steam can be made to enter the furnace it must be generated to a pressure greater than that in the furnace.

I claim—

1. The introduction of steam into the furnace of a hot-air engine in which pressure is maintained, when the steam is entered in immediate juxtaposition with the incandescent fuel for the purpose of wholly decomposing it into its constituent gases and mingling them

with the compressed heated air and gaseous products of combustion within the furnace.

2. Regulating the speed of hot air engines by automatically controlling the amount of steam admitted into the furnace with a valve in the steam-pipe connected with the furnace, when said valve is actuated by the engine-regulator.

H. MESSER.
